TYING MACHINE

Kim Yamasaki, Lombard, and Andrew L. Alger, Evans-
ton, Ill., assignors to B. H. Bunn Company, Chicago,
Ill., a corporation of Illinois

Filed Oct. 21, 1963, Ser. No. 77,052

Term of patent 14 years

(Cl. D55—1)

Fig. 1.

Fig. 2.

Fig. 3.

Fig. 4.

Fig. 5.

Fig. 6.

FIGURE 1 is a perspective view of a tying machine embodying our new design;

FIG. 2 is a side elevational view thereof;

FIG. 3 is a top plan view thereof;

FIG. 4 is a front elevational view thereof;

FIG. 5 is a rear elevational view thereof; and

FIG. 6 is a view taken on line 6—6 of FIG. 1, looking in the direction of the arrows.

We claim:
The ornamental design for a tying machine, substantially as shown.
